UNITED STATES PATENT OFFICE

165,980

ORANGE PEELER

Albert Howard, Brooklyn, N. Y.

Application June 27, 1950, Serial No. 10,776

Term of patent 7 years

(Cl. D22—3)

To all whom it may concern:

Be it known that I, Albert Howard, a citizen of the United States, residing in Brooklyn, county of Kings, and State of New York, have invented a new, original, and ornamental Design for an Orange Peeler, of which the following is a specification, reference being had to the accompanying drawing, forming part thereof, and in which:

Figure 1 is a front elevational view of an orange peeler, showing my new design.

Figure 2 is a rear view of the same; while

Figure 3 is an edge view thereof.

Figure 4 is a view taken on the line 4—4 in Figure 1.

Figure 5 is a view taken on the line 5—5 in Figure 1; while

Figure 6 is a view taken on the line 6—6 in Figure 1.

I claim:

The ornamental design for an orange peeler, as shown.

ALBERT HOWARD.
